J. KREM.
LIFE PRESERVING GARMENT.
APPLICATION FILED OCT. 12, 1912.

Patented Aug. 22, 1916.

UNITED STATES PATENT OFFICE.

JOHN KREM, OF PHILADELPHIA, PENNSYLVANIA.

LIFE-PRESERVING GARMENT.

1,195,365.

Specification of Letters Patent. Patented Aug. 22, 1916.

Application filed October 12, 1912. Serial No. 725,541.

To all whom it may concern:

Be it known that I, JOHN KREM, a subject of Austria-Hungary, residing at 244 South Fortieth street, Philadelphia, in the county of Philadelphia and State of Pennsylvania, have invented certain new and useful Improvements in Life-Preserving Garments, of which the following is a specification.

10 This invention relates to life preserving garments, the object being to provide a life preserving garment which is so made that the air will cause a body to stay at the surface of the water with only the head out 15 of the water.

Another object of the invention is to provide an air tight and water tight garment, with flexible pure rubber strips to be wound around the neck and wrists, to prevent 20 the water from getting in and wetting the body.

Another object of my invention is to fasten the opening edges of the garment, and roll the edges (after fastening with snaps) 25 up to the body and strap same.

Another object is to provide a life preserving garment that is easily applied in a very few minutes.

Another object of my invention is to provide 30 a fold in the suit which will compensate for different heights of persons using the life preserving garment.

These objects are obtained by the novel arrangements of parts hereinafter fully described and shown in the accompanying drawings, in which:

Figure 1 is the front view of my improved life preserving garment, placed upon a human being. Fig. 2 is a section through 40 the same as shown at 2-2 in Fig. 1. Fig. 3 is a sectional view of the leg of the garment, showing the strap fastening of the foot. Fig. 4 is a portional view of the top of the garment, showing the flexible pure 45 rubber strip and its place of fastening the same. Fig. 5 is a front view of the portion of the garment which is to be snapped together before rolling together. Fig. 6 is the paddle to be used in propelling the person.

50 Referring to the drawings, 7 indicates the canvas rubber strip of which the garment is made.

8 indicates the flexible pure rubber that is wrapped around the neck tightly, and 55 fastened through the ring 9 in Figs. 1 and 4.

10 indicates the fastened flexible pure

rubber strip onto the canvas rubber garment in Figs. 1, 4 and 5.

A indicates the front portion of the garment in Fig. 5 before it is fastened together 60 with the snaps J, and then it is rolled up, as shown at A Fig. 2, and then fastened by straps I with buckles shown in Figs. 1 and 2.

B indicates a flexible pure rubber bag in 65 Figs. 1 and 2 in front and back with a rubber bulb, to be used to keep the flexible pure rubber bag full of air, and this flexible pure rubber bag is securely fastened to the canvas rubber garment on the inside.

C indicates the rubber bulb. 70

D indicates the two pockets fastened onto the outside of the garment with snaps on the top of the pocket, and indicated by dotted circles in Fig. 1.

E indicates the paddle in Fig. 6 that is to 75 be hooked upon belt L as shown in Fig. 1.

F indicates a rubber sole as shown in Figs. 1 and 3 with a piece of lead fastened inside to keep the legs down in the water. The lead is indicated by G. 80

H indicates the strap with a buckle thereon in Fig. 3 holding the foot in place.

I indicates the straps as before mentioned.

J indicates the snaps as before mentioned.

K indicates the hook shown in Fig. 1 85 with hook K hooked over belt L. The life preserving garment takes a short time to be put on, and is very effective to keep the human body dry and warm in very cold water. 90

M indicates a cap in Fig. 1 as shown.

N in Fig. 1 is a stiff boot form which is fastened substantially to the foot and goes up near to the knee of the person and there fastened to the life preserving garment in a 95 water tight way, as shown in Fig. 1.

O in Fig. 1 represents a fold which is provided for the purpose of compensating for the different heights of persons who could use the life preserving garment. 100

Having thus described my invention, what I claim as new and desire to secure by Letters Patent is:

1. A life preserving garment composed of water proof material having a flexible and water proof neck band secured thereto at one end thereof and having a free end adapted to be wound around the wearer's neck and substantially held thereto by means of a ring, a wrist band secured at one end thereof to each of the sleeves of said garment and composed of the same material 105 110

- as said neck band and adapted to be wound around each wrist of the wearer and substantially held thereto by means of a second ring, a flexible bag secured to the inside of said garment and adapted to be inflated through the medium of a bulb, a series of pockets secured to the outside of said garment for the wearer's convenience, a weight substantially secured to the lower end of each leg of said garment, and a suitable means adapted to be hung on the belt of said garment as a means to be used by the wearer for propelling himself to safety as and for the purpose set forth.
15. 2. A life preserving garment composed of water proof material having a flexible and water proof neck band secured thereto at one end thereof and having a free end adapted to be wound around the wearer's neck and substantially held thereto by means of a ring, a wrist band secured at one end thereof to each of the sleeves of said garment and composed of the same material as said neck band and adapted to be wound around each

wrist of the wearer and substantially held thereto by means of a second ring, a means for access to said garment comprising a central front opening provided with means to increase or decrease the capacity of said garment, a flexible bag secured to the inside of said garment and adapted to be inflated through the medium of a bulb, a series of pockets secured to the outside of said garment for the wearer's convenience, a weight substantially secured to the lower end of each leg of said garment, a means provided on each of said legs for lengthening or shortening the same, and a suitable means adapted to be hung on the belt of said garment as a means to be used by the wearer for propelling himself to safety as and for the purpose set forth.

In testimony whereof I affix my signature in presence of two witnesses.

JOHN KREM.
